UNITED STATES PATENT OFFICE.

SAMUEL S. SARGEANT, OF NEWARK, NEW JERSEY.

DESIGN FOR A HARNESS-MOUNTING.

SPECIFICATION forming part of Design No. 12,598, dated December 13, 1881.

Application filed October 15, 1880. Term of patent 14 years.

To all whom it may concern:

Be it known that I, SAMUEL S. SARGEANT, of Newark, in the county of Essex and State of New Jersey, have invented and produced a new and original Design for Harness-Mountings; and I do hereby declare that the following is a full and exact description thereof, reference being had to the accompanying drawings, making part of this specification—
10 Figure 1 being an edge view of a terret formed according to my new design; Fig. 2, a section of the same in a horizontal plane below the body and looking down upon the base of the terret; Fig. 3, a top view of a check-hook formed according to my design; Fig. 4, a front view of the same.

Like letters designate corresponding parts in all of the figures.

The body A and base B of a terret, or the body or main part C of a check-hook, or the corresponding main part of other harness-mountings, being made of gold, or oide, silver, nickel, or other metal or alloy of good appearance and capable of polishing or otherwise receiving a handsome finish, I form on the flat principal outer surface of each stripes *a a*, of black or other suitable contrasting color of enamel. Figs. 1, 3, and 4 show two parallel stripes of

the enamel on the main outer surfaces, and Fig. 2 shows a single stripe of the enamel on 30 the base.

Harness-mountings being made in sets of similar design throughout, I apply this design, as usual, on the different kinds of the mounting elements in a manner and on such surfaces 35 as customary, this being well known in the art, and no further specification thereof is here needed. I form these stripes, in fact, of enamel set in grooves of the mountings, and contemplate this material especially in this design; 40 but I do not confine myself to this material, and I may use other materials which are sufficiently durable and furnish the requisite contrasting colors.

I claim—

The design for harness-mountings, which consists of stripes *a a*, alternating with the flat metallic body of the same, substantially as herein shown and described.

Specification of my new design for harness-mountings signed by me this 1st day of October, 1880.

S. S. SARGEANT.
